UNITED STATES PATENT OFFICE.

LAURENCE E. TOPHAM, OF SWAMPSCOTT, MASSACHUSETTS, ASSIGNOR TO UNITED SHOE MACHINERY COMPANY, OF PATERSON, NEW JERSEY, A CORPORATION OF NEW JERSEY.

LOCK-STITCH SEWING-MACHINE.

1,124,187.

Specification of Letters Patent.

Patented Jan. 5, 1915.

Application filed March 14, 1913. Serial No. 754,214.

To all whom it may concern:

Be it known that I, LAURENCE E. TOPHAM, a citizen of the United States, residing at Swampscott, in the county of Essex and State of Massachusetts, have invented certain new and useful Improvements in Lock-Stitch Sewing-Machines; and I do hereby declare the following to be a full, clear, and exact description of the invention, such as will enable others skilled in the art to which it appertains to make and use the same.

The present invention relates to lock stitch sewing machines, and more particularly to lock stitch sewing machines in which a stationary bobbin case is supported in a rotary hook which operates to cast the loop of thread around the bobbin case.

The object of the present invention is to provide an improved mechanism for holding the bobbin case stationary as the hook rotates.

With the above object in view, the present invention consists in the lock stitch sewing machine hereinafter described and particularly pointed out in the claims.

In the drawings which illustrate the preferred embodiment of the present invention, Figure 1 is a plan view; Fig. 2 is a section taken partially along the line 2—2 of Fig. 1; and Fig. 3 is a section taken partially along the line 3—3 of Fig. 1.

In the illustrated embodiment of the invention, the loop of thread drawn down by a hook needle is cast around the bobbin case 1 by means of a rotary hook, indicated generally by reference numeral 2. The hook comprises an annular body portion 3 and an inwardly directed thread-engaging beak 4 which enters the loop of thread drawn down by the needle and takes it from the barb of the needle. The annular body portion 3 of the hook has at its lower end an inwardly projecting flange 5 which is engaged in an annular raceway formed between the body 6 of the hook supporting frame 6 and a plate 7 secured to the top of the support. The hook makes three revolutions to each reciprocation of the needle and is continuously rotated in timed relation therewith by means of a bevel gear wheel 10 which meshes with bevel gear teeth 11 cut in the periphery of the annular hook body 3. The barbed needle (not shown) passes upwardly through the passage 12 in the hook supporting frame 6 and plate 7 and through the an-

nular body of the hook and draws down through the throat-plate of the machine a loop of thread which is entered by the beak 4. The loop of thread taken from the needle by the beak 4 slips into the thread-receiving groove 8 of the hook which acts to spread the loop of needle thread and carry it about the bobbin case 1. The hook support 6 is a frame of a substantially U-shaped outline having two legs 15 and 16 in the ends of which are formed co-axial bearings 17 and 18 by means of which the hook supporting frame 6 is hinged to the frame of the machine. The hook supporting frame 6 is given a limited oscillation about the axis of the bearings 17 and 18 once for every reciprocation of the needle so that the beak 4 will pass to the left, as viewed in Figs. 1 and 2, of the needle and thus clear the needle during the two idle rotations of the hook. The gear wheel 10 is mounted to rotate on a shaft 20 which is rigidly held in the supporting frame 6 and held in place by means of the nut 21. At the end of the hub 22 of the gear wheel 10 is formed a universal joint 23 through which the power is transmitted from a gear wheel 24 mounted to rotate upon a shaft 25 fixed to the machine frame. The universal joint 23 lies in the axis of the bearings 17 and 18 and permits a limited oscillatory movement of the hook supporting frame 6.

The above described parts have substantially the same construction and mode of operation as the corresponding parts illustrated and described in my co-pending applications for sewing machines, Serial No. 621,286, filed April 15, 1911, and for lock stitch sewing machines, Serial No. 698,458, filed May 20, 1912.

The bobbin case 1 is discoidal in outline and is rotatably mounted within the annular body 3 of the hook upon an annular plate 30 which is rigidly secured to the hook body 3 and which lies in a plane normal to the axis of rotation of the hook and the inner periphery of which is received in a raceway 31 cut around the periphery of the bobbin case 1. The bobbin case has in its top or upper end face a cup-shaped bobbin-receiving recess 32 in which is a central post 33 upon which is rotatably mounted a bobbin 34. The bobbin 34 is removably held in place by means of a spring-held latch 35.

The bobbin case 1 is prevented from rotat-

ing with the hook 2 by means of detent pins 40 and 41 which are arranged to engage circular recesses 42 and 43 drilled in the top of the bobbin case, one on each side of the bobbin-receiving recess 32. The pins 40 and 41 are formed upon the laterally extending arms 44 and 45 of two bell cranks 46 and 47. The arms 44 and 45 are substantially parallel and extend over the top of the bobbin case 5 upon each side of the bobbin-receiving recess 32, leaving sufficient space between them so that the bobbin can be readily taken out from the top of the bobbin case. The bell cranks 46 and 47 are co-axially fulcrumed 10 upon a shaft 50 which lies substantially in the plane of the flat top or upper end of the bobbin case 1. The shaft 50 is supported at its ends in ears 51 and 52 which are formed at the tops of upwardly extending posts 53 and 54 which are rigidly mounted in the frame 6 and are held by means of nuts 55 threaded on their lower ends. The shaft 50 is rigidly clamped in the ears 51 and 52 by means of pins 56, the sides of which are 15 recessed to receive the shaft 50 and which are drawn upwardly to clamp the shaft by means of nuts 57. The hubs 58 and 59 of the bell cranks 46 and 47 are elongated to properly space the bell cranks apart and to 20 afford a long bearing which prevents the detent pins 40 and 41 from getting out of alignment with the recesses 42 and 43. The bell cranks 46 and 47 are given a limited oscillatory movement during each rotation 25 of the hook by means of a cam 60 which is cut in the hub of the gear wheel 10. The cam 60 is engaged by cam rolls 61 and 62 mounted upon pins 63 and 64 which project from the ends of the downwardly extending 30 arms 65 and 66 respectively of the bell cranks 46 and 47. The gear wheel 10 has the same number of teeth as the bevel gear 11 on the rotary hook and consequently the detent arms 44 and 45 are raised and lowered once 35 during each rotation of the hook. The timing of the cam 60 is such that either one or the other of the detent pins 40 and 41 is in engagement with the bobbin case to hold it at all times against rotation, while the 40 detent pin which would be in the path of the needle thread passing over the top of the bobbin case is withdrawn to allow the needle thread to pass. The hook is rotated in the direction indicated by the arrow in Fig. 1. 45 After the loop of needle thread is taken from the barb of the needle, it is spread by the thread-receiving groove 8 and is carried about the bobbin case 1. The bottom leg of the loop is carried laterally (from right to 50 left, as viewed in Fig. 3) across the unobstructed bottom end face of the bobbin case. The upper leg of the loop is carried laterally (from right to left, as viewed in Fig. 3) over the upper end face of the bobbin case. 55 The thread which passes over the upper face

is first carried across the detent-receiving recess 43, the detent pin 41 being withdrawn to permit it to pass and the detent pin 40 being advanced to hold the bobbin case from rotation. After the loop of thread has been 60 distended to its maximum and is being drawn in, the thread passes over the detent-receiving recess 42, the detent pin 40 being raised to permit its passage and the detent pin 41 being advanced into engagement with 65 the bobbin case to hold it from rotation. 70

In order to prevent the needle thread from being caught on the detent pins 40 and 41, thread guards 70 and 71 are provided for the detent pins 40 and 41 respectively. The 75 thread guards 70 and 71 are formed upon the ends of arms 72 and 73 which are integral with the tops of the posts 53 and 54 respectively and which extend substantially parallel with, but outside of, the detent arms 80 44 and 45. The thread guard 70 consists of the two fingers 80 and 81 of the forked end 85 of the arm 72. The fingers 80 and 81 extend about half way around the pin 40 and loosely embrace it. When the detent pin 40 is fully 90 withdrawn from the bobbin case and into the thread guard, its free end is about at the level of the lower face of the thread guard 70, so that the thread cannot catch upon the end of the detent pin. The finger 95 81, as shown in Fig. 3, is thin so that it does not interfere with the downward movement 100 of the arm 44. The fingers 80 and 81 extend substantially in the direction in which the thread is moving as it is being pulled off from the bobbin case, so that there is no danger of the thread catching upon the free ends of the fingers. The thread guard 71 consists of the two fingers 82 and 83 of the 105 forked end of the arm 73. The fingers 82 and 83 extend substantially half way around and loosely embrace the detent pin 41. When the detent pin 41 is fully withdrawn from the bobbin case and into the thread guard, its free end is in substantially the 110 plane of the bottom of the thread guard so that the thread is prevented from catching on the pin. Since the thread which passes under the detent pin 41 is passing to the left and backwardly, as viewed in Fig. 3, in order 115 to prevent the thread from catching on the ends of the fingers 82 and 83, the finger 82 is short and the finger 83 is carried about half way across the front of the pin 41, as viewed in Fig. 3. The fingers 82 and 83 thus 120 extend in the general direction in which the thread is moving so that the thread passes away from the free ends of these fingers and cannot be caught upon them. The finger 82 which extends under the detent arm 45 is, 125 like the finger 81, thin so as not to interfere with the movement of the arm 45.

While the preferred embodiment of the present invention has been specifically illustrated and described, the present invention is 130

not limited to its illustrated embodiment but may be embodied in other constructions within the scope of the invention as set forth in the following claims.

5. I claim—

1. A lock stitch sewing machine having, in combination, a rotary hook, mechanism for driving the hook, a discoidal bobbin case about which the loop of thread is cast by the hook rotatably mounted in the hook and having a cup-shaped bobbin-receiving recess in its end face and two detent-receiving recesses in the same face one on each side of the bobbin-receiving recess, means for holding the bobbin case from rotation comprising two detent arms extending laterally over the end of the bobbin case upon each side of the bobbin-receiving recess and having detent pins for engaging the detent-receiving recesses in the bobbin case, mechanism for oscillating the arms to alternately advance and withdraw the detent pins so as to permit the needle thread to pass about the bobbin case, and means for preventing the needle thread from being caught on the detent pins comprising two fixed arms extending laterally over the end of the bobbin case and having at their free ends thread guards which loosely embrace the detent pins and into which the detent pins are withdrawn.

2. A lock stitch sewing machine having, in combination, a rotary hook, mechanism for driving the hook, a discoidal bobbin case about which the loop of thread is cast by the hook rotatably mounted in the hook and having a cup-shaped bobbin-receiving recess in its end face and two detent-receiving recesses in the same face one on each side of the bobbin-receiving recess, means for holding the bobbin case from rotation comprising two detent arms extending laterally over the end of the bobbin case upon each side of the bobbin-receiving recess and having detent pins for engaging the detent-receiving recesses in the bobbin case, mechanism for oscillating the arms to alternately advance and withdraw the detent pins so as to permit the needle thread to pass about the bobbin case, and thread guards for preventing the needle thread from being caught on the detent pins.

3. A lock stitch sewing machine having, in combination, a rotary hook, mechanism for driving the hook, a discoidal bobbin case about which the loop of thread is cast by the hook rotatably mounted in the hook and having a cup-shaped bobbin-receiving recess in its end face and two detent-receiving recesses in the same face one on each side of the bobbin-receiving recess, means for holding the bobbin case from rotation comprising two substantially parallel detent arms extending laterally over the end of the bobbin case upon each side of the bobbin-re-

ceiving recess and having detent pins for engaging the detent-receiving recesses in the bobbin case, mechanism for oscillating the arms to alternately advance and withdraw the detent pins so as to permit the needle thread to pass about the bobbin case, and means for preventing the needle thread from being caught on the detent pins comprising two fixed arms extending laterally over the end of the bobbin case and having their free ends forked to form thread guards which consist of fingers extending in the general direction of movement of the thread and loosely embracing the detent pins and into which the detent pins are withdrawn. 80

4. A lock stitch sewing machine having, in combination, a rotary hook, mechanism for driving the hook, a discoidal bobbin case about which the loop of thread is cast by the hook rotatably mounted in the hook and having a cup-shaped bobbin-receiving recess in its end face and two detent-receiving recesses in the same face one on each side of the bobbin-receiving recess, means for holding the bobbin case from rotation comprising two substantially parallel detent arms extending laterally over the end of the bobbin case upon each side of the bobbin-receiving recess and having detent pins extending toward the end face of the bobbin in directions substantially normal to the end face for engaging the detent-receiving recesses in the bobbin case, and mechanism for oscillating the arms to alternately advance and withdraw the detent pins so as to permit the needle thread to pass about the bobbin case. 95

5. A lock stitch sewing machine having, in combination, a rotary hook, mechanism for driving the hook, a discoidal bobbin case about which the loop of thread is cast by the hook rotatably mounted in the hook and having a cup-shaped bobbin-receiving recess in its end face and two detent-receiving recesses in the same face one on each side of the bobbin-receiving recess, means for holding the bobbin case from rotation comprising two bell cranks having substantially parallel arms extending laterally over the end of the bobbin case upon each side of the bobbin-receiving recess and having detent pins for engaging the detent-receiving recesses in the bobbin case, and mechanism located out of the plane of the end face of the bobbin case and engaging the other arms of the bell cranks for oscillating the bell cranks to alternately advance and withdraw the detent pins so as to permit the needle thread to pass about the bobbin case. 110

6. A lock stitch sewing machine having, in combination, a rotary hook, a frame upon which the hook is rotatably supported, mechanism for driving the hook, a discoidal bobbin case about which the loop of thread is cast by the hook rotatably supported by the 125

- hook and having a bobbin-receiving recess in its end face and two detent-receiving recesses in the same face one on each side of the bobbin-receiving recess, posts on the 5 hook supporting frame, a shaft mounted on said posts, two detent arms fulcrumed on said shaft and extending laterally over the end of the bobbin case one on each side of the bobbin-receiving recess and having at 10 their ends detent pins for engaging the detent-receiving recesses in the bobbin case, and mechanism connected with the hook driving mechanism for oscillating the arms to alternately advance and withdraw the detent pins so as to permit the needle thread 15 to pass about the bobbin case.
7. A lock stitch sewing machine having, in combination, a rotary hook, a frame upon which the hook is rotatably supported, 20 mechanism for driving the hook including bevel gear teeth on the hook, a bevel gear wheel mounted on the frame and meshing with the gear teeth on the hook and means for driving the bevel gear wheel, a discoidal 25 bobbin case about which the loop of thread is cast by the hook rotatably mounted in the hook and having a bobbin-receiving recess in its end face and two detent-receiving recesses in the same face one on each side of the bobbin-receiving recess, means for holding 30 the bobbin case from rotation comprising two bell crank levers fulcrumed on the hook supporting frame in approximately the plane of the end face of the bobbin case 35 in which the detent-receiving recesses are and having substantially parallel arms extending laterally over the top of the bobbin case upon each side of the bobbin-receiving recess and having detent pins on the free 40 ends of the detent arms for engaging the detent-receiving recesses in the bobbin case, a cam co-axial with the bevel gear teeth and connected with the bell cranks for oscillating them to alternately advance and withdraw the detent pins so as to permit the needle thread to pass about the bobbin case, and means for preventing the needle thread 45 from catching upon the detent pins comprising two fixed arms on the hook supporting frame extending laterally over the end face of the bobbin case and having at their free ends thread guards which loosely embrace the detent pins and into which the detent pins are withdrawn.
- 50 55 8. A lock stitch sewing machine having, in combination, a rotary hook, a frame upon which the hook is rotatably supported, mechanism for driving the hook including bevel gear teeth on the hook, a bevel gear wheel mounted on the frame and meshing with the gear teeth on the hook and means for driving the bevel gear wheel, a discoidal 55 bobbin case about which the loop of thread is cast by the hook rotatably mounted in the hook and having a bobbin-receiving recess 60 in its end face and two detent-receiving recesses in the same face one on each side of the bobbin-receiving recess, means for holding the bobbin case from rotation comprising two bell crank levers fulcrumed on the hook supporting frame in approximately the plane of the end face of the bobbin case 65 in which the detent-receiving recesses are and having substantially parallel arms extending laterally over the top of the bobbin case upon each side of the bobbin-receiving recess and having detent pins on the free ends of the arms for engaging the detent-receiving recesses in the bobbin case to hold the bobbin case from rotation, said bell crank levers having downwardly extending arms terminating at the hub of the bevel gear wheel, a cam on the hub of the bevel gear wheel connected with the downwardly extending arms of the bell crank levers for oscillating them to alternately advance and withdraw the detent pins so as to permit the needle thread to pass about the bobbin case, and means for preventing the needle thread from catching on the detent pins comprising two fixed arms extending substantially parallel with the detent arms and having at their free ends thread guards which loosely embrace the detent pins and into which the detent pins are withdrawn.
- 70 75 80 90 95 100 105 110 115 120 125 130 9. A lock stitch sewing machine having, in combination, a rotary hook, an oscillating frame on the top of which the hook is rotatably supported, mechanism for driving the hook including bevel gear teeth on the hook, a bevel gear mounted on the frame below the hook and meshing with the gear teeth on the hook and means for driving the bevel gear wheel, a discoidal bobbin case about which the loop of needle thread is cast by the hook rotatably supported in the hook and having a bobbin-receiving recess in its upper end face and two detent-receiving recesses in the same face one on each side of the bobbin-receiving recess, upwardly extending posts on the hook supporting frame, a shaft extending between said posts, two bell crank levers fulcrumed on the shaft and having arms extending laterally over the top of the bobbin case upon each side of the bobbin-receiving recess and having detent pins at the free ends of the arms for engaging the detent-receiving recesses in the bobbin case to hold the bobbin case from rotation, said bell crank levers having downwardly extending arms terminating at the hub of the bevel gear wheel, a cam on the hub of the bevel gear wheel connected with the downwardly extending arms of the bell crank levers for oscillating them to alternately advance and withdraw the detent pins so as to permit the needle thread to pass about the bobbin case, and means for preventing the needle thread from catching on the detent pins comprising two fixed arms extending substantially parallel with the detent arms and having at their free ends thread guards which loosely embrace the detent pins and into which the detent pins are withdrawn.
10. A lock stitch sewing machine having, in combination, a rotary hook, mechanism for driving the hook, a bobbin case about which the loop of thread is cast by the hook rotatably mounted in the hook and having detent-receiving recesses in one of its end

faces, means for holding the bobbin case from rotation comprising detent arms extending laterally over the end of the bobbin case and having detent pins extending toward the end face of the bobbin in directions substantially normal to the end face for engaging the detent-receiving recesses in the bobbin case, and mechanism for os-

cillating the arms to alternately advance and withdraw the detent pins so as to permit the needle thread to pass about the bobbin case. 10
